UNITED STATES PATENT OFFICE.

WILLIAM S. GRAFTON, OF WHEELING, WEST VIRGINIA, ASSIGNOR TO THE WHEELING CORRUGATING COMPANY, OF SAME PLACE.

DESIGN FOR A CORNER-PIECE FOR METALLIC MOLDING.

SPECIFICATION forming part of Design No. 23,051, dated February 6, 1894.

Application filed January 8, 1894. Serial No. 496,197. Term of patent 7 years.

To all whom it may concern:

Be it known that I, WILLIAM S. GRAFTON, a citizen of the United States, residing at Wheeling, in the county of Ohio and State of West Virginia, have invented and produced a new and original Design for Corner-Pieces for Metallic Molding, of which the following is a specification, reference being had to the accompanying drawing, forming a part thereof, which shows a corner-piece for metallic molding designed according to my invention.

My design consists of a corner-piece for metallic molding in which a square body-portion A, has sloping or tapered sides a, a', having ribs a², at their lower edges provided with concaved circular projections a³, arranged at equal distances apart. In each of the tapered sides a, a', there are oblong depressions a⁴. In the flat face of the body-portion A, there is a depression a⁵, occupying about one-half the area of the body-portion. Around the edge of the depression a⁵, there is a series of depressions a⁶, which are circular at their outer ends a⁷, and join each other by curved lines a⁸. A circular depression a⁹, is formed in the corner of the body-portion A. A relatively large, kite-shaped depression B, is arranged in the depression a⁵, between smaller,

spoon-shaped depressions b, both the kite-shaped depression and the spoon-shaped depressions being rounded by ribs or ridges. Projections or ribs C, are arranged at right angles to each other, and project from the lower corner of the depression a⁵. They connect with small inclined depressions c, which join the spoon-shaped ribs.

The essential feature of my design is a corner-piece for metallic molding having the body-portion formed with sloping or tapered sides, and a depression in the face of the body-portion, ornamented with a kite-shaped figure, arranged between and projecting from spoon-shaped figures, the upper, flat part of the body-portion having a series of depressions circular at their outer ends and joined by curved lines, and the tapered sides being provided with a series of oblong depressions.

I claim—

A design for a corner-piece for metallic molding herein shown and described.

In testimony whereof I have hereunto subscribed my name.

WILLIAM S. GRAFTON.
